UNITED STATES PATENT OFFICE.

FREDERICK W. MOORE, OF NEWARK, NEW JERSEY, ASSIGNEE TO LUXEMOOR COMPANY,
OF BOSTON, MASSACHUSETTS, A CORPORATION OF MASSACHUSETTS.

EMBOSSSED LAYER OF FELT.

1,115,232.

Specification of Letters Patent. Patented Oct. 27, 1914.

Application filed July 18, 1910, Serial No. 571,720. Renewed February 19, 1912. Serial No. 749,535.

To all whom it may concern:

Be it known that I, FREDERICK W. MOORE, a citizen of the United States, residing in Newark, county of Essex, and State of New Jersey, have invented an Improvement in Embossed Layers of Felt, of which the following description, in connection with the accompanying drawings, is a specification, like letters on the drawings representing

10 like parts.

This invention relates to a layer or sheet of felt having one or both of its surfaces provided with a design, which is formed by cutting projecting portions of said surface and simultaneously compacting and calendering the cut portions of said surface, whereby a superior product is obtained in which the design is sharply defined and the detail of which is made to stand out prominently. To 20 this end, the layer of felt is subjected to the action of a machine provided with a pattern surface having a series of wells or recesses which form molds into which portions of one surface of the sheet or layer are forced 25 under compression by a pressure member or roll, and cut off from the said surface by a knife having a thin cutting edge which is interposed between the felt sheet or layer and the pattern, so as to cut only the portions of 30 the surface which are confined in the molds or patterns. The knife cuts the projecting portions of the surface of the felt sheet or layer at the point of greatest compression and acts to compact and calender or iron the 35 portions of the felt surface from which the projections are cut, with the result, that the fiber of the cut portions of the felt have imparted to them a decidedly different appearance from those portions of the felt surface 40 which are not cut, so that the design formed by the cut portions are sharply defined and marked with respect to the uncut portions.

Figure 1 represents in plan a piece of felt embodying this invention. Fig. 2, a section 45 on the line 2—2; Fig. 1, and Fig. 3, a sufficient portion of a machine with which the product represented in Figs. 1 and 2 may be produced.

Referring to Fig. 3, *a* represents a pattern, 50 which is formed in the circumference of a roll *b* of metal, hard rubber or other solid material, and which is shown as resting upon and rotated by contact with a bed roll *c*. Above the pattern roll *b* with its axial center 55 in a vertical line with the axial center of the

pattern roll *b*, is a pressure roll *d*, which is separated from the pattern roll by a sufficient space to permit a sheet or layer *e* of felt to be fed under compression between the said rolls, so as to force or project portions of the 60 under surface 10 of the sheet or layer *e* into the molds, recesses or wheels *a* in the circumference of the pattern roll, said molds or recesses forming a pattern. The portions of the surface 10, which are forced under compression into the molds *a*, are confined therein in against lateral movement by the walls of the mold, and are therefore solidly supported, while they are cut off by the cutting edge 65 of a knife 12, preferably a traveling belt or band knife movable between suitable guides 13, and which is arranged with relation to the pattern roll, so that its cutting edge is interposed between the said roll and the surface of the felt sheet or layer adjacent 70 thereto.

The cutting edge of the knife is preferably made by curved, beveled or inclined surfaces of unequal length, the upper bevel or curve 14 being longer than the beveled or 75 curved surface 15, so that the cutting edge is below the medium line 16 of the knife, whereby a sharp, thin cutting edge is obtained, which is capable of being carried forward between the rolls *b*, *d*, to or in close 80 proximity to the vertical line through the axial centers of said rolls, at which point the felt sheet or layer is subjected to the greatest compression, and the cutting edge acts 85 tangentially with relation to the pattern 90 and severs the portion of the felt sheet or layer, which is projected from the under surface thereof into the mold, which is brought into the line of greatest compression. The cutting edge also forms a closure 95 for the mold as the pattern is moved toward the knife, and the upper surface of said cutting edge serves to iron or calender the cut portions of the under surface of the felt sheet or layer, whereby the fibers 20 of said 100 cut portions are compacted, smoothed and finished in sharp contrast to the fuzzy nature of the uncut portion 21 of said surface, thereby bringing out in detail and with clearness, the design formed by the cut 105 portions. The relatively loose or fuzzy appearance of the uncut portion 21 of the surface 10 of the felt layer or sheet is represented in Fig. 1 by the open appearance of the drawing, whereas the finished appear-

110

ance of the cut portions 20, which form the design, is represented by the close or fine appearance of the said cut portions.

The felt sheet or layer may be composed 5
of the same quality or different qualities or kinds of fiber, and in either case the design is sharply defined and a highly pleasing effect produced.

The machine with which the design is 10 produced in a felt sheet or layer, is not herein claimed, as it forms the subject-matter of a separate application, Serial No. 571,779, filed by me on July 13, 1910.

Any desired design may be obtained by 15 providing the proper or desired pattern.

In U. S. Patent No. 1,005,059 granted to me October 3, 1911, I have shown and described a product, which approximates the product herein shown and described, but 20 which differs therefrom in two respects. The product described in the patent referred to, is provided with layers of different texture, the outer layer being firmer than the inner layer of the fabric, and the design was made 25 by removing portions of the firmer outside layer, and the detail in the design was emphasized by the difference in color between the color of the firmer portion which was removed and the firmer portion left uncut 30 and forming the bottom of the design. In the present instance, the fibrous layer may be of one color throughout or it may be of two colors as in the patent referred to, but 35 in either case, the sharpness or detail of the design is brought out more by the difference in the appearance of the fibers of the cut and uncut portions. In the present instance, it will be observed that the knife employed is different from the knife of the 40 patent, in that the knife herein shown has

its upper beveled surface longer than the lower beveled surface and that the longer beveled surface extends beyond or below the median line of the knife, which enables the cutting edge formed by the two surfaces to 45 be made thin and brought near to the point of greatest compression, which is in the vertical line through the centers of the rolls b, d, and which thereby causes the upper surface of the thin cutting edge to iron and 50 compact the fibers of the bottom of the design, which changes the appearance of the cut and uncut portions and thereby produces the design, which is sharply and clearly defined in the fibrous layer of one texture or 55 quality of fiber. The shorter beveled lower surface of the knife enables the latter to be made of sufficient thickness at the vicinity of the thin cutting edge to obtain the rigidity desired in the knife necessary to produce 60 the ironing or compacting effect upon the fibers of the cut portion.

Claim:

As an improved article of manufacture, a flexible sheet or layer of felt having portions of an outer surface cut away to form a design in said surface, the fibers of the cut portion being more compact and smoother than the fibers of the uncut portion of said surface to impart to the portion in design a 70 finish whereby said design is sharply defined and brought out in detail, substantially as described.

In testimony whereof, I have signed my name to this specification in the presence of 75 two subscribing witnesses:

FREDERICK W. MOORE.
